Attorney

UNITED STATES PATENT OFFICE.

KIMBRO HENSLEY, OF LENOIR CITY, TENNESSEE.

DIRIGIBLE HEADLIGHT FOR LOCOMOTIVES.

Application filed June 16, 1925. Serial No. 37,504.

This invention relates to improvements in dirigible headlights and is more particularly adapted for use upon locomotives.

As is well known, the curves of railroad tracks are "banked", that is to say the outer rail of the curve is suitably elevated with respect to the inner rail, whereby the car or locomotive is tilted laterally while rounding the curve. These conditions are utilized in providing a means for effecting the automatic movement and control of the headlights so that the rays from the headlight will at all times be directed onto the tracks.

A further object of the invention is to provide a dirigible headlight for locomotives which includes a pendulum, the same depending from an oscillatory shaft, suitable means being associated with the headlight and the shaft whereby the movement of the headlight on its vertical axis will be controlled by the oscillatory movement of said shaft.

A further object is to provide a dirigible headlight for locomotives of the above mentioned character which is simple in construction, inexpensive, and furthermore adapted to the purposes for which the same is designated.

Other objects and advantages of this invention will become apparent during the course of the following description.

In the accompanying drawing forming part of this specification and in which like numerals are employed to designate like parts throughout the same:

Figure 1 is a side elevation of the dirigible headlight embodying my invention.

Fig. 2 is a sectional view taken approximately on line 2—2 of Fig. 1 looking in the direction of the arrows, and

Fig. 3 is a similar view illustrating a modification.

In the drawing wherein for the purpose of illustration is shown the preferred embodiment of my invention, the numeral 1 designates the base which is secured on the front of a locomotive in any suitable manner. Secured at its lower end on the forward end of the base 1 is the vertical post or standard 2 and rotatably supported on the upper end of this post or standard is the headlight designated generally by the numeral 3. As the headlight may be of any conventional construction, such as is now ordinarily used upon locomotives, a further detailed description thereof is not thought necessary, it being

understood of course that the headlight is adapted to swing on the upper end of the post about a vertical axis.

Arranged on the bottom of the headlight casing adjacent the rear end thereof is the segmental beveled gear 4. Adapted to mesh with this segmental beveled gear is the complementary segmental beveled gear 5 which is supported on the forward end of the oscillatory shaft 6, the same being journaled adjacent its respective ends in suitable bearings 7 provided in the upper ends of the spaced supporting brackets 8 and 9 respectively, the latter being secured at their lower ends on the rear portion of the base. A collar pin is secured on the rear end of the shaft 6 so as to prevent the accidental displacement of the shaft from its bearings.

Depending from the intermediate portion of the oscillatory shaft 6 and adapted to swing between the supporting brackets 8 and 9 is the pendulum 11.

Normally the parts of my improved dirigible headlight are disposed in the manner shown in Fig. 2 wherein the pendulum 11 lies in the same vertical plane with the supporting brackets, and this position is maintained so long as a locomotive is traveling on a straight stretch of tracks. When the locomotive rounds a curve and consequently tilts inwardly of the curve on account of the fact that the outer rail of the track is higher than the inner rail, the pendulum 11 will swing correspondingly thus causing the shaft 6 to oscillate and simultaneously swinging the headlight 3 on its vertical axis through the medium of the intermeshing gears 4 and 5 so that the rays of light from the headlight will be directed onto the tracks while the locomotive is making the turn.

After the locomotive has passed beyond the curved portion of the track, it is of course apparent that the pendulum 11 will swing back to its initial position simultaneously returning the headlight to its normal position on the post or standard 2 so that the rays of light will be projected straight ahead.

In Fig. 3 of the drawing, the oscillatory shaft 6 is supported adjacent its respective ends in a pair of ears 12 which extend upwardly from the sides of a suitable container 13 which is supported on the rear portion of the base 1, said container being adapted to be filled with a liquid preferably

heavy oil and the pendulum 11 extends through the cut out portion 14 provided therefor in the top of the container, the weighted portion of the pendulum being 5 adapted for swinging movement in the body of oil placed within the container.

It will thus be seen from the foregoing description, that a dirigible headlight has been provided which is of such construction 10 as to enable the same to be readily and easily installed on the front of a locomotive and will furthermore at all times be positive and efficient in its operation so as to insure the proper illuminating of the tracks ahead of 15 the locomotive.

While I have shown the preferred embodiment of my invention, it is to be understood that various changes in the size, shape and arrangement of parts may be resorted 20 to without departing from the spirit or sacrificing any of the advantages of the appended claim.

What is claimed is:—

A dirigible headlight for locomotives comprising in combination, a base, a vertical post supported thereon, a headlight casing adapted to swing on a vertical axis on the upper end of said post, a closed liquid container mounted on the base rearwardly 25 of the standard, a pair of upstanding ears 30 formed on the forward and rear ends of the container, the top of said container being provided with a transversely extending slot, an oscillatory shaft journaled at its respective 35 ends in said upstanding ears, intermeshing segmental gears carried by the bottom of the rear portion of the headlight casing and the forward end of the oscillatory shaft respectively, and a pendulum depending from the intermediate portion of said oscillatory 40 shaft through the slot in the top of the casing, the lower end of the pendulum being operable within the liquid in the aforementioned container.

In testimony whereof I affix my signature.

KIMBRO HENSLEY.
